UNITED STATES PATENT OFFICE.

HENRY EWOLDT, OF GRAND ISLAND, NEBRASKA.

CABLE-GUIDE.

1,308,667.

Specification of Letters Patent.

Patented July 1, 1919.

Application filed December 16, 1918. Serial No. 266,990.

To all whom it may concern:

Be it known that I, HENRY EWOLDT, a citizen of the United States, residing at Grand Island, in the county of Hall and State of 5 Nebraska, have invented new and useful Improvements in Cable-Guides, of which the following is a specification.

This invention relates to devices for extricating automobiles and other motor vehicles out of mud holes and other soft places in the road, the same consisting of a winding drum connected to one or both drive wheels of the car, on which drum is adapted to be wound a cable or other hauling line, so 10 that upon setting the wheels in motion, the car is hauled out of the place in which it is mired.

The present invention relates more particularly to the means for guiding the hauling line, which latter, when it is to be used, must be anchored ahead of the car, and it is the object of the invention to provide simple and efficient guiding means, so attached to the car, that they can be swung out 20 of the way when not in use, and thus not mar the appearance of the car.

The object stated is attained by means of a novel combination and arrangement of parts to be hereinafter described and 30 claimed, and in order that the same may be better understood, reference is had to the accompanying drawing forming a part of this specification.

In the drawing,

35 Fig. 1 is an elevation showing the application of the invention;

Fig. 2 is an inverted plan view showing the line guide devices;

Fig. 3 is a side elevation thereof;

40 Fig. 4 is a top plan view, and

Figs. 5 and 6 are sections on the lines 5—5 and 6—6, respectively, of Fig. 4.

Referring specifically to the drawing 5 denotes a motor vehicle having applied to 45 one of its drive wheels 6 a winding drum 7 to which is attached a cable or other hauling line 8 extending forwardly, and anchored ahead of the car, to a stake or other suitable means 9. Upon throwing in the clutch, the 50 wheel 6 is put in motion, and the line 8 is wound on the drum 7, whereupon the car is caused to move forward, and in this manner is pulled onto the solid road bed out of the sink hole, sand, mud or other place in which 55 it may be stalled.

The line 8 is guided by certain devices

mounted on the running board 10 of the car 5. These devices are so mounted on the under side of the running board that they may be swung out of the way and out of 60 sight when not in use, and they consist of rear and forward guides, and an intermediate guide and tension member.

The rear guide comprises a block 11 having an elongated guide opening 12 in which 65 is mounted a horizontal anti-friction roller 13. The top of the block has a slot 14 which extends to the opening 12 so that the line 8 may be inserted into the latter. From the rear end of the block 11 extends a shank 15 70 which is pivoted to the running board 10, as shown at 16. The device is so positioned beneath the running board that it is completely concealed beneath the same and out of the way when not in use, and when it is 75 to be used, it is swung to extend outward therefrom, with the opening 12 clear of the running board. In the latter position, the opening 12 is so positioned that its longer dimension is transverse of the car.

For holding the device in the two positions described, the under side of the running board 10 carries two stop blocks 17 to which are secured projecting spring tongues 18. When the device is folded back beneath the running board, as shown dotted in Fig. 2, the shank 15 engages one of the stop blocks and is engaged by the projecting spring tongue of that block, whereby the device is securely held and prevented from accidentally swinging outward from beneath the running board. The other stop block and its spring tongue engages the shank 15 when the device is swung outward into position for use, and securely holds it in this position.

The forward line guide is a grooved vertical roller 19 journaled on a shaft 20 carried by an arm 21 pivoted to the running board 10 as shown at 22. This device is also mounted beneath the running board and is foldable beneath the same as the rear guide device hereinbefore described. Stop blocks 23 and spring latch tongues 24 for holding the device in the two positions are also provided.

To the top side of the arm 21 is pivoted, as shown at 25, a guard plate 26 adapted to be swung to come over the roller 19 to prevent the line 8 from slipping down off the latter. 110 The free end of the guard plate has a notch 27 so that it may be slipped over the end of

the shaft 20, whereby it is held in place. Before the line can be applied to the roller 19, the guard plate must first be swung clear of the latter, and after the line is in place, 5 the plate is swung back over the roller and locked in place by placing the notch 27 over the shaft 20.

The intermediate guide and tension device comprises two opposite rollers 28 and 10 29, respectively, between which the line 8 is adapted to be passed. The roller 28 is on a stationary support, and the roller 29 is carried by a swinging support and held 15 yieldingly pressed toward the roller 28 to tension the line.

The support for the roller 28 is a channeled plate 30, the roller being mounted in the channel. This plate is carried by a base plate 31 pivoted to the running board 10, on 20 the underside thereof, as shown at 32, for the same purpose as the front and rear guide devices hereinbefore described. Stops 33 and spring latch tongues 34 are also provided for holding the base plate 31.

25 The support for the roller 29 is also a channeled plate 35, pivoted at one end to the plate 30 as shown at 36, so that it may swing toward and from the latter. The free end

of the plate 35 is engaged by a spring 37 coiled around a rod 38 extending from the 30 plate 30 and passing loosely through an aperture in the plate 35. This spring presses down against the back of the plate 35, and therefore yieldingly holds the roller 29 35 pressed toward the roller 28 for tensioning the line 8.

I claim:

1. The combination with the running board of a motor vehicle; of hauling line 40 guide devices pivotally mounted on the under side thereof, said devices being adjustable to project outward from the running board, and also foldable beneath the same, stops on the running board engageable respectively by the guide devices in the two 45 positions stated, and spring latch tongues projecting from said stops and engageable with the devices for holding the same.

2. The combination with the running board of a motor vehicle; of hauling line 50 guide devices mounted thereon at the respective ends thereof and an intermediate guide and line tensioning device on the running board.

In testimony whereof I affix my signature. 55
HENRY EWOLDT.
